UNITED STATES PATENT OFFICE.

JOHN G. TALMAGE, OF CLEVELAND, OHIO.

METHOD OF AND APPARATUS FOR DISTRIBUTING LUBRICATING-OIL UNDER STEAM-PRESSURE.

1,337,179.

Specification of Letters Patent. Patented Apr. 13, 1920.

Application filed January 24, 1919. Serial No. 272,962.

To all whom it may concern:

Be it known that I, JOHN G. TALMAGE, a citizen of the United States, residing at Cleveland, in the county of Cuyahoga and State of Ohio, have invented a certain new and useful Improvement in Methods of and Apparatus for Distributing Lubricating-Oil under Steam-Pressure, of which the following is a full, clear, and exact description, reference being had to the accompanying drawings.

This invention is concerned with the effective lubrication of a plurality of devices subjected to steam pressure, as for example, the cylinder and steam chest of a locomotive. Many existing locomotives have a single pipe leading from the lubricator and branching to the cylinder and steam chest. In such constructions it is difficult to properly divide the oil between the steam chest and cylinder, because the pressure in the cylinder varies from the boiler pressure to almost nothing while the pressure in the steam chest is frequently nearly constant, continuing for long periods at substantially the boiler pressure. I have discovered a very simple method by which the distribution from a single pipe to the cylinder and steam chest may be maintained in the desired ratio, irrespective of varying pressures. By my method the cylinder and steam chest may receive equal quantities of oil, or any other proportion desired of the total amount fed. My invention includes the method by which I accomplish this and also the apparatus which I prefer to employ for carrying out such method. The invention is hereinafter more fully explained and its essential characteristics are summarized in the claims.

In the drawings, Figure 1 is a side elevation of a portion of a locomotive, showing the cylinder, steam chest and lubricating pipes and embodying my distributing apparatus; Fig. 2 is an enlarged vertical section of the distributing device; Figs. 3, 4 and 5 are respectively cross sections of the distributing device on the correspondingly numbered lines on Fig. 2; Fig. 6 is an enlarged vertical section through one of the choke plugs employed in the apparatus; Fig. 7 is an end view of such plug; Fig. 8 is a vertical section through a drifting valve which is shown in side elevation in Fig. 1 and which may constitute a portion of the lubricating conduit to the steam chest;

Figs. 9 and 10 are diagrams explaining the distribution of oil, Fig. 9 illustrating a case where half of the oil goes to each of two distributing passageways and Fig. 10 a case where one distributing passageway receives three times as much oil as the other.

As shown in Fig. 1, A indicates the locomotive cylinder, B a steam chest, C the dry pipe supplying steam to the steam chest, D a drifting valve communicating with the steam chest, E a steam supply pipe to the drifting valve leading from the boiler. The drifting valve is provided with internal arrangements hereinafter described to cause the admission of steam from the pipe E to the steam chest whenever the pressure therein drops to a predetermined minimum, the throttle being closed. This drifting valve, however, provides a constantly open oil conduit to the steam chest, and its particular characteristics form no portion of the present invention.

In Figs. 1 and 2, 10 indicates the main lubricating pipe leading from the lubricator and adapted to supply oil under boiler pressure. 11 indicates my distributing device hereinafter described; 12 a pipe from the distributing device to the steam chest, this pipe being coupled with the top of the drifting valve D, and 13 a pipe from the distributing device to the cylinder.

Referring now to Figs. 2 to 7 inclusive, the body of the distributing device consists of a Y-shaped member having a central chamber 20, a tubular extension 21 communicating therewith and in communication with the main pipe 10 and two branch tubular extensions 22 and 23 communicating with the pipes 12 and 13 respectively. Each of the tubular extensions is coupled with its respective pipe by a screw threaded flange member, as the flanged nut 24 coupling the extension 21 with the pipe 10, the nut 25 coupling the extensions 22 with the pipe 12, and the nut 26 coupling the extension 23 with the pipe 13.

Threaded into a reduced central portion of each of the extensions is a plug designated respectively 30, 32 and 33. This plug, in the present embodiment, is of the general type shown on an enlarged scale in Fig. 6. It has an enlarged central portion provided with an external thread 35, has a central bore 36 extending through it from end to end and various lateral openings designated 37 lead-

ing to the central bore. These lateral openings are for the purpose of providing extra entrances for oil in case of clogging and may be disregarded as far as the operation is concerned.

The plugs 30, 32 and 33 constitute chokes for the passage of oil and are all just alike with the exception of the area of the passageways, which are specially proportioned 10 as hereinafter explained and constitute an important factor in this invention.

I have discovered that if the passageway 36 through the plug 30 in the main lubricating pipe has an area equal to, or larger than, 15 the combined areas of the passageways 36 through the plugs 32, and 33, the oil is distributed in proportion to the relative areas of these passageways in the plugs 32 and 33, irrespective of the pressures in the pipes 12 20 and 13. By way of illustration, if the passageway 36 in the plugs 32 and 33 have equal areas, one-half of the oil fed through the choke plug 30 passes to the pipe 12 and one-half to the pipe 13. If the passageway 25 in the plug 32 has an area twice that of the passageway in the plug 33, twice as much oil will go to the pipe 12 as to the pipe 13, provided the sum of the areas in the passageways of the two plugs 32 and 33 does not 30 exceed the area of the passageway in the plug 30. In other words, if the sum of the areas in the two distributing passageways is no greater than the area of the main passageway the distribution of oil is in proportion 35 to the areas of the two distributing passageways, and this is independent of the relative pressures in the two distributing pipes, as well as independent of the velocity of the fluid.

40 Figs. 2 to 5 inclusive illustrate a construction where the two passageways 36 in the plugs 32 and 33 are equal in area, and the sum of these areas is equal to the area of the passageway 36 in the main plug 30. In the 45 preferred construction, the sum of the areas of the openings in the two distributing plugs is equal to the area of the opening in the main plug, but no harm results, through a decreased efficiency, if the area of the passageway in the plug 30 is greater than the 50 sum of the areas of the passageways in the two distributing plugs. On the other hand, the desired operation does not result if the area of the passageway in the plug 30 is less than the sum of the areas of the other two 55 passageways.

Fig. 9 is a diagram illustrating the distribution of oil where the sum of the areas of the two distributing passageways is equal 60 to that of the main passageway and the two distributing passageways are individually equal. The legend A=4 indicates that the area of the passageway in the plug 30 is four units while the legends A=2 indicate that 65 the area of each of the distributing passageway

ways is two units. In such case what may be called four units of oil coming through the passageway 30 is distributed, two units to the passageway 32 and two to the passageway 33, as indicated by the two sets of two lines, 70 designated P². Fig. 10 illustrates a corresponding construction where the areas of the passageways in the plugs 33 and 32 bear the relation of 1 to 3, as indicated by the legends A=3 and A=1. The sum of these areas, 75 however, are equal to the area of the passageway in the plug 30, as indicated by the legend A=4. In this case if we assume that four units of oil passes through the passageway in the plug 30, one unit, indicated by 80 the line P', passes to the passageway 33, while three units, indicated by the three lines P³, pass to the passageway 32.

By the system described, I am able to distribute to the cylinder and valve chest exactly 85 the quantities of oil desired, and this is independent of the relative pressures against which the oil is fed and independent of the boiler pressure feeding the oil.

Experience with the device and method 90 has proven that the result stated is accomplished. The physical laws which cause this result are at present unknown to me, as the result is contrary to natural expectations as to the operation of the apparatus employed. 95 My experience indicates, however, that the result is due to the fact that the lubricating oil is broken up into globules when passing through the plug 30, and that those globules move through the distributing chokes at a 100 speed which is independent of the pressures. The steam which pushes the oil along seems to move faster through the passageway leading to the pipe having the lower pressure but apparently this steam moves past the globule 105 of oil and does not increase its speed of travel. In this system of lubrication the drops of oil occur only at intervals, steam being in the intervening spaces, and the present theory of operation is that when such 110 steam is opposed by a materially lower pressure of steam it rushes past the globule of oil which is retarded by its engagement with the wall of the passageway, so that this globule is not increased in speed by an increased 115 velocity of the steam in the passageway.

I have found that the device operates to a certain extent but not so satisfactorily if it is standing out of the vertical position shown. From this it would seem that gravity is a factor in the distribution. I have further found that the device ceases to distribute the oil in proportion to the areas if the area of the admission passageway is less than the sum of the other two. The 125 area of the admission passageway may be increased beyond the sum of the other two areas provided the admission area is maintained small enough to break the oil into globules. I find that I can vary the two dis- 130

tributing passageways as desired and effect a corresponding distribution in the quantity of oil to the two distributing pipes, provided I do not allow the total areas of the 5 distributing passageways to exceed the area of the main passageway.

While my experience indicates that the device and operation may be employed with various boiler pressures and various quantities of oil and various sizes of passageways, provided the proper relative areas are maintained, it may be noted by way of 10 example that very satisfactory results with the most usual conditions in locomotives, 15 namely, two hundred pounds pressure and a lubrication of twelve drops per minute, are obtained, by making the diameter of the passageway in the main choke plug approximately five sixty-fourths of an inch, 20 and selecting such diameters for the openings in the distributing chokes that the sum of their areas shall be equal to the area of a circle five sixty-fourths of an inch in diameter. 25 On account of the small diameters of the choke passageways, there is a possibility of impurities in the oil clogging the passageways, though the high pressure of the steam tends to keep them clean. To provide for 30 this, I have made a number of lateral passageways 37 in each plug so that if any become clogged there are others available. The clogging, if any, naturally occurs adjacent to the entrance of the passageway. In 35 case of absolute clogging it is only necessary to uncouple the device by unscrewing the nuts 24, 25 and 26 and remove the clogged plug. This removal is readily effected by applying a wrench to the squared outer end 40 of the plug, such squared end being illustrated in Fig. 7.

As the various plugs differ only in areas of their passageways, it is convenient, from a manufacturing standpoint, to make them 45 all alike so far as their exterior is concerned, and drill them with different sized openings. As the plug which occupies the main passageway receives the oil at its squared end while the other two plugs receive the oil at the other ends, I make the 50 plugs reversible and adapted to be used either end foremost. Accordingly I provide the screw threading on an enlarged intermediate portion of the plug and extend the 55 plug each way from the screw threading, there being the lateral openings 37, referred to, in each of these end extensions. The extensions are materially smaller than the tubular member they occupy to provide for 60 the entrance of fluid to the lateral passageways and the discharge of fluid from such passageways.

While the drifting device shown in Figs. 1 and 8 is independent of my invention, I 65 may explain that, as shown, it is made in

accordance with Patent No. 1,188,796, issued to me June 27, 1916, on an application of Frank M. Lickley. As shown in Fig. 8 hereof, and as described in that patent, the drifting valve contains a single unitary 70 member 40 which carries a disk valve 41, between an intake member 42 and a chamber 43 communicating with the valve chest, and above has a piston 44 of an area slightly larger than that of the disk valve, occupying 75 a cylindrical portion of the casing, and above this piston has a piston 46 occupying an enlarged cylindrical portion of the casing, and being of considerably greater area than a piston 44. The stem connecting the 80 disk valve and the two pistons has a central bore 47. A cap 48 on the casing has a passageway 49 for oil through a tubular member coupled with the pipe 12. The passageways 49 and 47 and the top and bottom 85 chambers of the drifting device provide a continuous oil conduit from the pipe 12 to the steam chest. This enables the oil coming through the pipe 12 to lubricate both the drifting valve and the steam chest. 90

The purpose of the drifting valve is to prevent any vacuum forming in the steam chest when the locomotive is running with the throttle closed, and this prevention is effected by supplying boiler pressure steam 95 to the steam chest whenever the pressure therein drops below a certain minimum.

In ordinary running the steam chest pressure acting upwardly through the chamber 43 and the passageway 47 presses downwardly on top of the piston 46 and maintains the valve 41 closed. When, however, the pressure in the steam chest drops to a certain allowable minimum (as, for example five pounds per square inch) such reduced 100 pressure on the piston 46 is not sufficient to overcome the force of the boiler pressure through the pipe E acting upwardly on the slight excess of area of the piston 44 over the area of the disk valve 41. Accordingly 110 at such time, the pressure in the pipe E lifts the piston 44 and disk valve and thus allows boiler pressure to enter the passageway 43. This prevents the pressure in the steam chest ever dropping below the zero 115 line, which obviates the bad effect of a negative pressure in the steam chest. As soon as the pressure in the steam chest is restored above a desired minimum the valve 41 seats and the drifting valve becomes idle. 120 Whether the drifting valve is seated or is active, there is always an open passageway for lubricating oil to the steam chest.

Having thus described my invention, what I claim is:

1. The method of distributing oil under steam pressure to a plurality of locations through a main conduit and branches, comprising breaking the oil up into globules, then causing it to pass while subject to the 130

- propelling influence of gravity through a plurality of passageways, the sum of the areas of which do not exceed the area of the passageway which broke the oil into globules.
2. The method of distributing oil under steam pressure to a plurality of locations through a main conduit provided with branches, comprising choking the bore of the main conduit sufficiently to break the oil into globules, and choking the bores of the branch conduits so that the sum of their areas does not exceed the area of the main choke.
3. The method of distributing oil under steam pressure to a plurality of locations through a main conduit with branches, comprising choking the bore of the main conduit and choking still more the bores of the branch conduits, so that the sum of the areas of the minimum passageways in the branches shall not exceed the area of the minimum passageway in the main conduit.
4. The method of distributing lubricating oil under steam pressure, comprising providing main and branch conduits having passageways, the sum of the areas of the branch passageways being no greater than the area of the main passageway, and the passageways being sufficiently vertical so that the oil is subject at least to some extent to the propelling influence of gravity.
5. An apparatus for distributing lubricant, comprising a main conduit and a plurality of branch conduits, and choke plugs in the respective conduits provided with passageways, the combined areas of the passageways through the choke plugs of the two distributing conduits being no greater than the area of the passageway through the choke plugs in the main conduit.
6. An apparatus for distributing oil under steam pressure, comprising a Y-connection coupled with a main lubricating pipe and two distributing pipes and choke plugs in the stem and branches of the Y, each having a tubular passageway, the sum of the areas of the passageways in the branch choke plugs being not greater than the area of the passageway in the main choke plug.
7. The system of distributing oil from a common passageway to two branch passageways, consisting of providing three passageways with chokes, the sum of the areas of the openings in the chokes in the two distributing passageways being equal to the area of the opening of the choke in the main passageway.
8. The system of distributing oil from a common passage to a plurality of branch passageways in any desired proportion consisting of providing the common passageway and the branch passageways with chokes, the sum of the areas of the openings in the chokes of the branch passageways being no greater than the area of the choke in the common passageway, and the areas of the individual choke openings in such branch passageways being mutually proportioned corresponding to the required division of oil between them.
9. The system of distributing oil to a plurality of passageways in different quantities from a common passageway, consisting of the provision in the distributing passageway of chokes the openings of which have areas which are individually different but the sum of which is not greater than the area of the minimum opening in the common passageway.
10. An apparatus of the character described, comprising a member having a main passageway and a plurality of branch passageways, and choke plugs in the respective passageways, the combined areas of the openings through the choke plugs of the several distributing passageways being not greater than the area of the opening through the choke plug in the main passageway.
11. An apparatus for distributing oil comprising a Y-connection between a main passageway and two distributing passageways, a choke plug in each connection, each choke plug having a passageway through it, and the sum of the areas of the passageways of the two distributing chokes being not greater than the area through the passageway of the main choke.
12. An apparatus of the character described, comprising a substantially vertical member having an internal chamber, an admission passageway thereto and discharge passageways therefrom, choke plugs in the respective discharge passageways having longitudinal openings, and means for choking the admission passageway sufficiently to break the oil into globules in its passage to said chamber.
13. In a device of the character described, the combination of a Y-shaped member, having an internal chamber, a tubular passageway leading to such chamber, two passageways leading from such member, means for coupling pipes with the three passageways mentioned, a plug screw threaded into each of said passageways, said plug having a bore, the sum of the areas of such bores in the two distributing plugs being not greater than the area of the bore of the plug in the common portion of the device.
14. In an apparatus of the character described, the combination of a connection having three tubular arms communicating with an internal chamber, flanged couplings for connecting pipes with the three arms, each arm having an internal thread, a plug screwing into said thread, said plug having longitudinal passageway, the area of the

passageways of the plugs in the two branch arms being no greater than the area of the passageway of the plug in the main arm.

15. In an apparatus of the character described, the combination of a connection having three tubular arms communicating with an internal chamber, each arm having an internal thread, a plug screwing into said thread, said plug having longitudinal passageways, the area of the passageway of the plugs in each of the branch arms being less than the area of the passageway of the plug in the main arm, each plug having a threaded portion which engages the arm and

15 an angular extension.

16. In an apparatus of the character described, the combination of a connection having three tubular arms communicating with an internal chamber, each arm having an internal thread, a plug in each arm screwing into said thread, each plug having a longitudinal bore, and lateral passageways extending through its body into the bore thereof.

25 17. In an apparatus of the character described, the combination of a member having a plurality of tubular conduits commu-

nicating with an internal chamber, a plug screwing into each of said conduits, each of said plugs having a longitudinal bore, each 30 plug having an intermediate threaded portion and two sets of openings extending through its body into the bore thereof, said sets being at the opposite ends of the plug respectively.

35 18. In an apparatus of the character described, the combination of a device having tubular arms communicating with an internal chamber, each arm having a portion which is internally threaded, a plug externally threaded and screwing into the thread of the arm, said plug having a longitudinal extension within the arm beyond the screwing thread, a longitudinal opening through the plug, a lateral opening in the body of 45 the plug communicating with the longitudinal opening and located at said inward extension of the plug, there being an annular space surrounding said extension of the plug within the arm carrying it.

50 In testimony whereof, I hereunto affix my signature.

JOHN G. TALMAGE.
